UNITED STATES PATENT OFFICE

ARTHUR J. BRAUER AND FREDERICK P. WAGNER, OF ST. LOUIS, MISSOURI

DEVICE FOR ATTACHING WOODEN HEELS

Application filed March 4, 1931. Serial No. 520,029.

This invention relates generally to the manufacture of shoes, and particularly to a device for temporarily attaching wooden heels in position during the manufacture of the shoe.

In the manufacture of shoes, and especially those which are provided with wooden heels, it is the usual practice that the heel be secured by means of cement to the heel seat which is provided usually as a part of the outer sole. During the time in which the cement is setting, it is necessary, however, to securely clamp the wooden heel in its alined position on the heel seat. Various devices have heretofore been used for accomplishing this result. The device most commonly in use is perhaps a screw, which extends through an opening in the heel part of the last, having a pointed end in engagement with the wooden heel and a suitable shoulder engaging the top of the heel part of the last, so that a clamping action results. With the use of devices of this sort, however, it is necessary to preliminarily drill the wooden heel for a sufficient depth to receive the securing screw, so as to prevent splitting of the heel upon the application of the screw. The devices which have heretofore been in use possess the further disadvantage of being entirely separate from the last so that it has been necessary for an operator to arrange the screw in the hole provided in the heel part of the last before he proceeded to drive it home, in order to clamp the heel in position. In the manufacture of shoes on a large scale, where it is the duty of a single operator to do nothing more than cement and clamp wooden heels in position, it is apparent that the amount of time consumed by the operator in drilling the wooden heel for the reception of the clamping screw, as well as the time consumed by the operator in selecting and inserting a screw of appropriate length for a particular job, is immense, and it is accordingly an object of this invention to provide a device for temporarily securing wooden heels in position while the cement is setting which will eliminate the two aforementioned steps.

The object of this invention, generally

stated, is to provide a device for temporarily securing a wooden heel in position while the cement is setting.

A further object of this invention is to provide a temporary heel-securing device which is permanently mounted upon a last.

A further object of this invention is to provide a device for temporarily securing heels which is normally concealed by the last and projectible to engage a wooden heel.

A further object of this invention is to provide a device for attaching wooden heels which will not necessitate preliminary drilling of the heel.

Other objects will become apparent to those skilled in the art when the following description is read in connection with the accompanying drawing, in which:

Figure 1 is a view in side elevation of a last shown partly in section to reveal the heel-attaching device constructed in accordance with this invention;

Figure 2 is a view partly in section of the heel part of a last having a shoe and wooden heel mounted thereupon; and

Figure 3 is a detail view illustrating the component parts of the heel-attaching device constructed in accordance with this invention.

In accordance with this invention, the heel part of the usual last is provided with a bore extending therethrough, which has mounted therein a suitable device for attaching and clamping a wooden heel in position upon the last. In the preferred embodiment of this invention, the heel-attaching device is resiliently mounted within the bore and is normally biased in such a direction that the wood heel-engaging part is retracted into the bore and thus concealed by the last and so an unobstructed heel surface exists. With such an arrangement, the inner and outer soles and the upper are applied and lasted in the usual way, the heel seat is formed to fit the heel and a coating of cement applied to the heel and heel seat, as is the usual practice. The heel may then be placed in alinement upon the heel seat and a suitable tool inserted in the opening in the heel part of the last to force the heel-attaching device out.

wardly from the bore, and if, as in the preferred embodiment of this invention, the attaching device is in the nature of a screw, the projecting tool will preferably also im-
5 part to the attaching device a turning movement. With a device of this character, and especially since the heel-attaching device is, when not engaged with a heel, retracted in-
to the bore in the heel part of the last so that
10 it will not be subject to be struck by other objects and thus dull the threads, it becomes possible to form the screw threads of the attaching member in such a way that they are sufficiently sharp to perform not only the
15 securing and clamping function, but also to cut their way into the wooden heel, thereby eliminating the necessity of the preliminary boring operation.

20 Referring now particularly to the drawing, the usual last is shown provided with a heel part 1 having the usual thimble 2 for the reception of a jack post. In the embodiment shown in the drawing, the last is provided with a suitable metallic plate 3 extending
25 across the bottom thereof and secured in position by any suitable device, such as, for instance, the screws 4. The construction just described is in accordance with the usual last construction, and it will be understood
30 that the following description will set forth a method whereby the usual last may be modified by the application of the heel-attaching device constructed in accordance with this invention.

35 In order to prepare the usual last for the reception of a heel-attaching device constructed in accordance with this invention, the heel plate 3 will first be removed from the heel part 1 of the last. After the heel plate is removed a bore 5 may be drilled into the heel part extending substantially in the same direction as the axis of the wooden heel seated upon the last would extend. As shown in Figure 1, the bore 5 does not ex-
40 tend for the full distance through the heel part of the last, but that a counter bore 6 of smaller diameter is provided near the top part of the last, thus forming a shoulder 7 for a purpose to be later described. The heel
45 part of the last is now prepared to receive the heel-attaching device constructed in accordance with this invention.

50 A heel-attaching device constructed in accordance with this invention comprises a screw member 8 having a substantially long shank 9 and a head 11 provided with any suitable arrangement for cooperating with a driving tool. It is to be understood that any suitable type of head 11 may be provided
55 according to the desires of the users. The threaded part 12 of the screw 8 is in accordance with this invention extremely slender, and the threads thereof are highly sharpened. A tubular mounting member 13 hav-
60 ing an external diameter substantially the

same as the diameter of the bore 5, is pro-
vided for mounting the screw 8 within the bore 5. The mounting member 13 is pro-
vided on the interior thereof with an inward-
ly extending shoulder 14, shown clearly in
70 Figure 2, against which a coil spring 15 is seated. The coil spring 15 surrounds the shank 9 of the screw 8, and at its other end is seated against the head 11 of the screw. It is thus apparent that the spring 15 oper-
ates to bias the head of the screw 8 in an axial direction and away from the shoulder 14. The organization including the mounting member 13, the screw 8 and the spring 15 is applied as a unit to the bore 5, and the
75 heel plate 3 may be then placed in position in order to secure the heel-attaching organi-
zation within the bore 5. It will be noted
that the end of the mounting member 13,
80 which is to abut against the heel plate 3, is
inclined to the axis thereof, so that an even
bearing face parallel to the surface of the
85 heel plate 3 is provided.

90 When the device is assembled and the heel plate 3 is secured in position, it is apparent that the spring 15 will operate to bias the screw 8 axially within the bore 5, so that the head 11 engages the shoulder 7 and the threaded part 12 of the screw is at this time concealed within the confines of the bore 5,
95 so that the sharp threads thereof are not sub-
ject to injury by contact with other objects. The heel plate 3 is provided with a suitable opening 16 to permit the threaded part of
100 the screw 8 to pass therethrough.

When the heel seat of the shoe has been pre-
pared for the reception of the heel and the
preliminary operations completed, a wooden
105 heel such as 17, is placed in position upon
the heel seat 18 of the shoe, in which the last
having a heel part 1 is mounted and a suitable
tool such as 19, inserted into the bore 6 to en-
gage the head 11 of screw 8. Sufficient force
is applied through the tool 19 to force the
110 screw 8 against action of spring 15, and thus
to cause the threaded part 12 of the screw 8
to project outwardly through the opening 16
in the heel plate 3 and into engagement with
the heel 17, as illustrated in the dotted lines
115 of Figure 2. When the screw 8 has been driv-
en into engagement with the heel 17, it is ap-
parent that a positive clamping engagement
is present to maintain the heel 17 in its prop-
er alinement upon the last and upon the heel
120 seat 18, while the cement is setting; it being
apparent that the clamping force is trans-
mitted through the screw 8 and spring 15 to
the mounting member 13, and it is thus sus-
tained by the heel plate 3.

125 From the foregoing description, it is ap-
parent that the heel-attaching device of this
invention may be used without preliminarily
boring the heel and that the heel-attaching
organization is permanently carried in the
130 heel of the particular last with which it is

used, thereby eliminating the time heretofore consumed by a workman in selecting a screw of the proper length for the particular last, as well as the time consumed by the workman 5 in preliminarily drilling the heel for the reception of the screw.

It will, therefore, be seen that in accordance with this invention a last adapted to receive a soled shoe for the application of a heel and 10 having a heel part, has a device permanently associated with the heel part, this device having an operative anchoring element constructed and arranged to engage and become anchored in the heel so as to clamp the heel 15 against the shoe while on the last. This operative anchoring element is not only projectable through the last bottom and the sole thereon and into the heel, but this element, as previously stated, is so constructed and arranged as to secure an anchoring hold in the heel. This is accomplished in accordance 20 with the embodiment described by so arranging the anchoring elements as to be substantially unrestrained in order to permit it to 25 enter and become anchored in the heel. As described, a yielding abutment is provided in the form of a spring 15 which, while it is adapted to permit the anchoring element to enter and become anchored in the heel, nevertheless permits this anchoring element without substantial restraint to enter the heel and 30 become anchored therein. As this spring, however, becomes tensioned, it will serve to hold the anchoring element under tension so 35 as to finally clamp the heel against the shoe.

It is apparent that many modifications of this invention will present themselves to those skilled in the art which will not depart from the spirit thereof; accordingly, it is to be distinctly understood that the invention is not 40 limited to the specific details of construction hereinbefore described and illustrated in the accompanying drawing, but that the foregoing description is merely an exemplification 45 of a preferred embodiment and that such modifications thereof as do not depart from the spirit of this invention are contemplated by and within the scope of the appended claims.

50 Having thus described the invention, what is claimed is:

1. A last adapted to receive a soled shoe for the application of a heel and having a heel part, and a device permanently associated with said heel part, said device having an operative anchoring element constructed and arranged to engage and become anchored in the heel so as to clamp the heel 55 against the shoe while on the last.

60 2. A last adapted to receive a soled shoe for the application of a heel and having a heel part, and a device permanently associated with said heel part, including an operative anchoring element projectable through 65 the last bottom and the sole thereon and into

the heel, said element being constructed and arranged to become anchored in the heel so as to clamp the heel against the shoe while on the last.

3. A last adapted to receive a soled shoe 70 for application of a heel and having a heel part, and a device permanently associated with said heel part, said device having an operative anchoring element constructed and arranged to engage and become anchored in 75 the heel so as to clamp the heel against the shoe while on the last, said device having a tool engageable part formed to secure its manipulation.

4. A last adapted to receive a soled shoe 80 for the application of a heel and having a heel part, and a device permanently associated with and contained within said heel part, including an operative anchoring element projectable through the last bottom and 85 the sole thereon and into the heel, said element being constructed and arranged to become anchored in the heel so as to clamp the heel against the shoe while on the last.

5. A last adapted to receive a soled shoe 90 for the application of a heel and having a heel part, and a device permanently associated with and contained within said heel part, including an operative anchoring element provided with a tool engageable part 95 and an anchoring part which is projectable through the last bottom and the sole thereon and into the heel, said element being constructed and arranged to become anchored in the heel so as to clamp the heel against the 100 shoe while on the last.

6. A last adapted to receive a soled shoe 105 for the application of a heel and having a heel part, and a device permanently associated with said heel part, including an operative anchoring element projectable through the last bottom and the sole thereon and into the heel, said element being substantially unrestrained to enter and become anchored in 110 the heel so as to clamp the heel against the shoe while on the last.

7. A last adapted to receive a soled shoe 115 for the application of a heel and having a heel part, and a device permanently associated with said heel part, including an operative anchoring element projectable through the last bottom and the sole thereon and into the heel, said element being substantially unrestrained to enter and become anchored in 120 the heel, and an abutment for retaining said element in anchoring relation while in the heel, so as to clamp the heel against the shoe while on the last.

8. A last adapted to receive a soled shoe 125 for the application of a heel and having a heel part, and a device permanently associated with said heel part, including an operative anchoring element projectable through the last bottom and the sole thereon and into the heel, and a yielding abutment adapted 130

to permit said element to enter and become anchored in the heel so as to clamp the heel against the shoe while on the last.

9. A last adapted to receive a soled shoe
5 for the application of a heel and having a heel part, and a device permanently associated with said heel part, including a screw operatively projectable through the last bottom and the sole thereon and into the heel,
10 said element being substantially unrestrained to enter and become anchored in the heel so as to clamp the heel against the shoe while on the last.

10. A last adapted to receive a soled shoe
15 for the application of a heel and having a heel part, and a device permanently associated with said heel part, including a screw operatively projectable through the last bottom and the sole thereon and into the heel, and
20 a spring adapted to permit said screw to enter and become anchored in the heel so as to clamp the heel against the shoe while on the last.

25 In testimony whereof, we affix our signatures this 19th day of February, 1931.

ARTHUR J. BRAUER.
FREDERICK P. WAGNER.
